UNITED STATES PATENT OFFICE.

ROBERT C. COLE, OF HARTFORD, CONNECTICUT, ASSIGNOR TO THE JOHNS-PRATT COMPANY,
OF HARTFORD, CONNECTICUT, A CORPORATION OF CONNECTICUT.

INCLOSED FUSE.

No. 895,431.

Specification of Letters Patent. Patented Aug. 11, 1908.

Application filed January 31, 1907. Serial No. 355,019.

To all whom it may concern:

Be it known that I, ROBERT C. COLE, a citizen of the United States, residing at Hartford, in the county of Hartford and State of Connecticut, have invented certain new and useful Improvements in Inclosed Fuses, of which the following is a full, true, and concise specification.

My invention relates to inclosed fuses, and has special reference to an improved construction of such fuses wherein the gases generated upon the disruption of the inclosed fuse-link may be effectually and safely vented without loss of the comminuted refractory material with which the fuse inclosure is usually packed, and my invention rests on the discovery, which I have made, that by covering the usual vent-holes of such inclosure with a screen composed of a number of overlaid or woven filaments or threads such as ordinary cotton threads and having lint or fuzz thereon, the gases of disruption are permitted to discharge readily and freely through the vent-holes, but the powder and fine particles of the filling material are retained within the casing. By thus freely venting the gases of disruption, the pressure and rise of temperature within the fuse inclosure is kept substantially normal, so that the tendency for an arc to form between the inclosed fuse-link terminals is greatly reduced, if not entirely obviated.

In Figure 1 I exhibit an ordinary inclosed fuse in longitudinal section, supplied with the screen of my invention; and in Fig. 2 a magnified section of said screen.

The construction of the fuse of Fig. 1 comprises a fuse-link 1, connected to fuse-link terminals 2, 2 at each end and surrounded by a mass of comminuted refractory material 3, such as crushed lime or gypsum. The fuse-link inclosure comprises a cylindrical fuse-tube or casing 4 and end closures therefor, in the form of metallic ferrules 5, to which the said fuse-link terminals 2, 2 are respectively connected so that current may pass from ferrule to ferrule through the link, in the usual and well understood manner.

The ferrules are each provided with one or more vent-holes, indicated by 6, and according to my invention the screen 7, placed against the inner ends of the ferrules over

the vent-holes, is comprised of a single layer of cotton gauze, preferably the commercial hospital gauze such as is ordinarily used by surgeons for bandages, etc. This material is made of loosely woven threads or filaments consisting of twisted cotton fibers with the free ends of many of the fibers projecting laterally from them forming a lint or nap thereon, thus forming a reticulated or sieve-like fabric with the interstices occupied largely by the nap, which serves in practice to prevent the escape of the fine filling material through the vent-holes, but at the same time does not seem to offer any substantial obstruction to the expanding gases.

Fig. 2 is intended to illustrate on a magnified scale the general structure of the gauze screen referred to, but it is to be understood that my invention contemplates other forms of screens and screens of other material than cotton, provided the same have an elastic lint or fuzz upon them like the lint on cotton threads.

Having described my invention, what I claim and desire to secure by United States Letters Patent, is—

1. In an inclosed fuse, the combination with the fuse link and comminuted filling material, of a fuse inclosure therefor having means for venting the same comprising one or more open vent-holes adapted to provide a free escape for the expanding gases and a reticulate screen formed of liny or fuzzy material with its interstices occupied by the lint or fuzz thereon and serving to retain the said comminuted material without appreciably obstructing the gases.

2. In an inclosed fuse, the combination with the fuse-link and comminuted filling material, of an inclosure therefor having means for venting the same comprising a plurality of vent-holes adapted to provide a free escape for the gases of combustion and a screen for said vent-holes composed of twisted fibers having lint or nap upon them serving to retain the said comminuted material without appreciably obstructing the gases.

3. In an inclosed fuse, the combination with the fuse link and comminuted filling material, of an inclosure therefor having means for venting the gases of combustion

comprising one or more open holes and a cotton gauze screen of such texture as will retain the said comminuted material within the inclosure while permitting free and substantial immediate escape of the gases through the said vent-holes.

In testimony whereof, I have signed my

name to the specification in the presence of two subscribing witnesses.

ROBERT C. COLE.

Witnesses:

ARTHUR B. PECK,
JOHN S. FITZSIMMONS.
